UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,603, dated August 28, 1894.

Application filed August 3, 1894. Serial No. 519,375. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an arrangement of lines and ornamental scrolls forming a series 10 of panels with ornamental figures of Venetian style in the center of said panels and smaller panels containing fleur-de-lis ornaments as represented in the accompanying drawing. The border or upper portion of the design is 15 formed of ornamental lines at top and bot-

tom forming an open panel in which are placed similar ornaments of Venetian style as shown in the drawing.

What I claim is—

1. The design for wall paper herein shown 20 and described.

2. In the design for wall paper, the border herein shown and described.

Witness my hand this 31st day of July, 1894.

CHARLES BOOZE.
